UNITED STATES PATENT OFFICE.

FRANK M. McLEROY, OF GAINESVILLE, GEORGIA.

PLUMB-LEVEL.

No. 857,891.

Specification of Letters Patent.

Patented June 25, 1907.

Application filed June 18, 1906. Serial No. 322,277.

To all whom it may concern:

Be it known that I, FRANK M. McLEROY, a citizen of the United States, residing at Gainesville, in the county of Hall and State 5 of Georgia, have invented a new and useful Plumb and Level, of which the following is a specification.

This invention relates to plumbs or levels and has for its object to provide improved 10 means for illuminating the level bubble or tube thereby to permit the operator to readily ascertain the plumb or level of an object in, using the instrument at night or when working in dark or poorly lighted places.

15 A further object of the invention is to provide a level having a push-button arranged in one side thereof and connected with the terminals of a battery, the latter being connected in series with an incandescent lamp 20 whereby the several liquid tubes may be illuminated by depressing the push-button.

A still further object of the invention is to generally improve this class of devices so as to increase their utility, durability and efficiency 25 as well as to reduce the cost of manufacture.

With these and other objects in view the invention consists in the construction and 30 novel combination and arrangement of parts hereinafter fully described, and illustrated in the accompanying drawings, it being understood that various changes in form, proportions and minor details of construction 35 may be resorted to within the scope of the appended claims.

In the accompanying drawings forming a part of this specification: Figure 1 is a longitudinal sectional view of a level constructed in accordance with my invention. Fig. 2 is 40 a side elevation of the same. Fig. 3 is a transverse sectional view taken on the line 3—3 of Fig. 1. Fig. 4 is a similar view taken on the line 4—4 of Fig. 1.

Similar numerals of reference indicate corresponding parts in all of the figures of the drawings.

The improved instrument consists of a substantially rectangular body portion 5 provided with a transverse recess 6 in which are seated a plurality of spirit tubes or level bubbles 7 as shown. Arranged on each side of the body portion 5 and covering the opening 6 is a glass plate or closure 8 retained in position by means of a clamping ring 9.

The walls of the recess 6 are formed with a 55 V-shaped depression in which is seated a reflector 10 having a central opening formed therein for the reception of an incandescent lamp 11.

Formed in one end of the body portion 5 is 60 a chamber 12 for the reception of one or more cells of a battery 13, said chamber being closed by a plate 14 detachably secured to the end of the level so that the cells may be conveniently removed and recharged when 65 necessary. Communicating with the chamber 12 is a longitudinal opening or passage 15 in which are seated wires or conductors 16 connecting the lamp with the battery 13 and intersecting said passage is a transverse opening 17 extending through one side of the body of the level. Threaded in the opening 17 is a housing 18 in which is mounted a push-button 19 the latter being provided with contact plates 20 and 21 connected in any suitable 70 manner to the terminals 22 of the battery circuit so that by depressing the push-button 19 the bulb 11 may be lighted thereby to illuminate the spirit levels and thus permit the operator to ascertain the plumb or level of any 75 desired object. By having the reflector arranged at the top of the level the rays of light will be reflected downwardly and laterally and thus effectually illuminate all the spirit tubes or levels while by reason of the push-button the lamp may be readily lighted or extinguished at will.

From the foregoing description it will be seen that there is provided an extremely simple, inexpensive and efficient device admirably adapted for the attainment of the ends in view.

Having thus described the invention what is claimed is:

A leveling instrument comprising a body 95 portion having a chamber formed in one end thereof and provided at its opposite end with a transverse recess the walls of which are formed with a conical shaped depression, a reflector of less width than the body portion 100 engaging the walls of the depression and provided at its apex with an aperture, there being a longitudinal opening extending centrally through the body portion and connecting the chamber and aperture in the reflector and intersected by a transverse opening, spirit tubes seated within the recess, and arranged at right angles to each other, a bat-

tery disposed within the chamber, a lamp extending through the aperture in the reflector for illuminating the spirit tubes, conductors disposed within the longitudinal opening and connecting the lamp with the battery, transparent plates disposed on opposite sides of the body portion and bearing against the reflector to form closures for the tube-receiving recess, clamping rings engaging the transparent plates, and a push button seated in the

transverse opening and connected with the terminals of the battery circuit for controlling the lamp.

In testimony that I claim the foregoing as my own, I have hereto affixed my signature ¹⁵ in the presence of two witnesses.

FRANK M. McLEROY.
